UNITED STATES PATENT OFFICE.

JOHN I. PILSTON, OF WYANDOTTE, MICHIGAN.

PIPE-EXPANDING MACHINE.

1,108,618.

Specification of Letters Patent. Patented Aug. 25, 1914.

Application filed October 31, 1913. Serial No. 798,396.

To all whom it may concern:

Be it known that I, JOHN I. PILSTON, a citizen of the United States, residing at Wyandotte, county of Wayne, State of Michigan, have invented a certain new and useful Improvement in Pipe-Expanding Machines, and declare the following to be a full, clear, and exact description of the same, such as will enable others skilled in the art to which it pertains to make and use the same, reference being had to the accompanying drawings, which form a part of this specification.

This invention relates to pipe expanding machines and has for its object a machine adapted to expand the end of a pipe into an annular groove of a pipe flange so as to fasten the two members together. This machine is also adapted to turn the extreme end of the pipe over and against the flange.

In the drawings,—Figure 1, is a front elevation of the machine. Fig. 2, is a vertical section through the machine, showing some of the parts in elevation. Fig. 3, is a detail of the screw that forces the holding pins against the pipe flange. Fig. 4, is a fragmentary plan view of the cross head and its guides. Fig. 5, is a view of the hammer and the angular holder partly in elevation and partly in section. Fig. 6, is the bottom view of the angular holder. Fig. 7, is a view of the angular bracket by which the angular holder is attached to the supply pipe. Fig. 8, is a sectional detail of the rock shaft, the two levers and the segment supported thereby.

The frame of the machine comprises a casting *a* which is nearly square (Fig. 1) and which has a large central opening *b*. The base may be formed by such a casting as is shown in Figs. 1 and 2 and designated *c*. The castings *a* and *c* are fastened together. A pair of blocks *d* are adjustable sidewise and horizontally by loosening the nut and T-headed bolt *e* that runs in the groove *f* on the inside of the block. A pair of vertically sliding blocks *g* are adjustable vertically by the hand screws *h*. The bolts *i* projected into slots in the vertical blocks act as guides. The lower block *g* carries a shoulder *j* that can support the pipe flange *k*. The horizontally sliding blocks *d* also have shoulders *j*. These blocks form holders for the pipe flange when used in connection with the alining studs *l* which are pointed and can be brought to protrude through the perfora-

tions of the pipe flange. These alining studs hold the pipe flange firmly against the blocks. The ends of the blocks on the inside are beveled off so that if the hammers should hit them it will hit a glancing blow. The adjustability is to bring the blocks into proper relation with different sized flanges. The studs *l* are threaded through the ends of the alining arms *m* which are carried upon and adjustable vertically on the squared shaft *n*. The squared shaft *n* terminates in an arm *o* that has slots in its end which may be caused to straddle the pivoted screw *p* (Fig. 3). The hand nut *p* runs upon this screw and when the pivoted screw is swung into the slot the nut may be jammed up against the arm to securely hold the alining studs in the perforations of the flange.

The hammer is a pneumatic one such as I have shown and described in my previous application Serial Number 729,988. However, I have designed a new holder for the purpose of beading over the end of the pipe against the beveled opening of the flange, as shown in Fig. 2. The angular holder comprises a sort of T-shaped casting in which the hammer is bolted to the casting at one side of the stem of the T with the bottom of the hammer abutting against the under side of the bar of the T. The angular holder might be described as a right-angled casting with one side extended somewhat beyond the plane of the intersecting side. The angular holder is arranged to hold the hammer at an angle of about forty-five degrees to the vertical. The side of the casting that lies along the bottom of the pneumatic hammer casing including the extension is bored from end to end. Each end is plugged by a plug. Along the outside of this side of the casting are a plurality of tap holes *q* plugged by plugs *r*; the other or stem side of the T of the casting is bolted to the hammer casing and it is traversed lengthwise by a bore *s* that connects with the interior of the hammer casing through the branch passages *t*. These connect with a longitudinal passageway *u* in the side wall of the hammer casing. This passageway *u* leads inside of the hammer casing at the extreme bottom. This arrangement of passageways just described in connection with the stem of the T-shaped casting allows the use of the same hammer as is used for perpendicularly-struck blows upon the pipe, such as are best suited for

driving the pipe into the annular groove of the flange. However, the hammer preferably has a V-shaped groove on the end of the striking member to do the beading of the pipe into the flange. In my previous application, already alluded to, I have described such a hammer casing and hammer; the very hammer casing and hammer used for the work described in detail in my previous application and which is adjustable radially may be used with the angular holder shown in Fig. 5.

The angular bracket *v* comprises a casting, such as shown in Figs. 5 and 7, which has a nipple intended to be set horizontally and a flange set at an angle of approximately forty-five degrees. This flange is boltable to the bar member of the T casting which forms the angular holder. It may be bolted at a plurality of places along this portion of the angular holder so as to bring the passageway *w* in registry with any one of the tap holes *g*. In the form shown, (Fig. 5) any one of the four positions may be occupied by the angular bracket. In the position shown in Fig. 5 the bracket and holder are bolted together to get the greatest radial adjustment of the hammer. By occupying the successive relative positions the radial adjustment of the hammer is at three different times reduced. The hammer is disposed at approximately one hundred thirty-five degrees with respect to the supply pipe *x*.

The supply pipe *x* threads into the threaded end of the bracket. The supply pipe is rotatable in the cross head *y* and at its opposite end is provided with a hand wheel *z* by which it may be turned thereby turning the hammer while it is working. A flexible conduit, not shown, may be used to supply compressed air or the operating fluid. The cross head *y* is slidable on the guide rods 1, 1 and links 2 connect the cross head with an arm 3 that is fast to the shaft 4 which is journaled in the saddle 5. This saddle 5 is fastened to the top of the base *c* and serves also as a journal for the rotatable supply pipe *x*. The segment 6 is also fast to the shaft 4 while the lever 7 is loose upon the shaft, but this may be bolted to the segment 6 at any one of several perforations 8 along the outer edge of the segment. A stationary segment 9 is fastened to the saddle 5 and pins 10 may be placed in any of the perforations in this stationary segment to act as stops to limit and determine the arc of swing of the lever 7. The supply pipe *x* has a collar 11 that abuts against the cross-head so that movement of the slide moves the hammer. The hammer is moved back and forth by operating the lever 7 with one hand, while the hammer is revolved by turning the hand wheel *z* with the other hand. The amount of travel of

the hammer back and forth is determined by the position of the pins 10 upon the stationary segment 9. The distance of the operating range of the hammer with respect to stationary parts of the machine is controlled by the position of the lever 7 with respect to the segment 6.

What I claim is:

1. The combination of means for supporting a pipe flange, a rotatable supply pipe, a bracket on the end of said rotatable supply pipe provided with a passage therethrough, a holder adjustably connectible to said bracket and provided with a passage that connects with the passage of the bracket at selected positions, the said holder being adjustable across a face of the bracket which face lies at an angle of about forty-five degrees to the supply pipe, and an expanding tool supported by the holder at an angle of approximately one hundred thirty-five degrees with respect to the axis of the supply pipe, said expanding tool having a passage connecting with the passage of the holder.

2. The combination with means for supporting a pipe flange, of a supply pipe that is rotatable, a bracket provided with a passage carried on the end of the supply pipe, a holder provided with a passage connected with the passage of the bracket, said holder being angularly disposed with respect to the bracket, and an expanding tool disposed at an angle of approximately one hundred thirty-five degrees with respect to the supply pipe by reason of the angular disposition of the holder and the bracket, the said expanding tool being provided with a striking tool having a V-shaped recess on its end.

3. The combination with means for supporting a pipe flange, of a rotatable supply pipe, an angular bracket carried on the end of the same, an angular holder comprising a T-casting, a pipe expanding tool carried by the T-casting, the said angular bracket and holder having passageways for the operating fluid, and the angular bracket being connectible at various points along the T-casting to vary the radial projection of the expanding tool, substantially as described.

4. The combination with means for supporting a pipe flange, of a rotatable supply pipe, a bracket carried on the end thereof comprising a nipple and an angularly disposed flange, an angular holder comprising a T-casting bored for the passageway of the operating fluid and having a plurality of tap holes, the said angular bracket and T-casting being connectible at selectable places to vary the radial projection of the holder and a pipe expanding tool fastened to the holder and angularly disposed with respect to the plane of the pipe flange.

5. The combination of means for supporting a pipe flange, a rotatable supply

5 pipe, a pipe expanding tool carried on the end of the supply pipe, a sliding cross-head connected with the supply pipe to shift the same but to allow the same to rotate within the cross-head, a lever for operating the cross-head, and adjustable stops for limiting the travel of the cross-head, substantially as described.

10 6. The combination of means for supporting a pipe flange, a rotatable supply pipe, a pipe expanding tool carried on the end of the supply pipe, a slideable cross-head connected with the supply pipe to shift the same but to allow rotation thereof, a pivoted lever, linkage connecting the lever and the cross-head, a stationary segment, and pins fixable on the stationary segment at selected places to engage with the lever and control the range of operability of the expanding tool.

15 7. The combination of means for supporting a pipe flange, a rotatable pipe, an expanding tool carried on the end of the pipe, a sliding cross-head having a connection with the pipe to shift the same but to allow rotation thereof, a pivoted lever, linkage between the sliding cross-head and the lever, and means for connecting the said lever at different positions with respect to the linkage, for the purpose of changing the position of the operative range of the expanding tool, substantially as described.

20 8. The combination of means for supporting a pipe flange, a rotatable supply pipe, an expanding tool carried on the end thereof, a sliding cross-head having a connection to shift the supply pipe but to allow rotation thereof, a link connected to the cross-head and an arm attached to the opposite end of the link, a shaft properly journaled and fast to the end of the arm, a segment provided with a plurality of perforations and also fast to the shaft, a lever rotatably mounted upon said shaft, and means for bolting a lever through any one of the 45 perforations of the segments, substantially as described.

25 9. The combination of a casting or a frame for holding a pipe flange, a plurality of arms provided with alining studs adapted to be projected into the perforations of the flange, a shaft to which the arms are secured, an arm fastened to said shaft and provided with a bifurcated end, and a screw pivoted to the casting or frame, and adapted to be swung into the bifurcated end and turned to tighten the arm against the casting, substantially as described.

30 In testimony whereof, I sign this specification in the presence of two witnesses.

JOHN I. PILSTON.
